UNITED STATES PATENT OFFICE.

HERMAN HOFF, OF BUFFALO, NEW YORK.

LOCK FOR WINDOW SASHES, ETC.

Application filed July 31, 1922. Serial No. 578,563.

To all whom it may concern:

Be it known that I, HERMAN HOFF, a citizen of the United States, residing in Buffalo, in the county of Erie and State of New York, have invented new and useful Improvements in Locks for Window Sashes, &c., of which the following is a specification.

This invention relates to a sash lock which is designed to prevent unauthorized opening 10 of a sash from the exterior of the building and also to prevent the sash from rattling in windy weather.

It is the purpose of this invention to provide a sash lock or fastener for this purpose 15, which is comparatively simple and inexpensive in construction, which can be readily applied to the standard types of window sashes, as now generally constructed and in which the locking or stop member, when moved out 20 of its operative position remains permanently connected with the bracket upon which it is mounted so that loss of the same will not occur and thus always retain the same at hand where the same is ready for 25 use in locking the sashes against opening.

In the accompanying drawings: Figure 1 is a fragmentary perspective view of a pair of opposing window sashes and the adjacent part of the window frame equipped 30 with my improved sash lock or fastener. Figure 2 is a horizontal section, taken on line 2—2, Fig. 1 and showing the sash locked in its operative position. Figure 3 is a similar view but showing the sash lock 35 in its inoperative position. Figure 4 is a fragmentary vertical transverse section taken on line 4—4, Fig. 2. Figure 5 is a similar section taken on line 5—5, Fig. 3. Figure 6 is a vertical longitudinal section, 40 on an enlarged scale, taken on line 6—6, Fig. 2. Figure 7 is a perspective view of the holder and guide for the locking block showing these members made integrally. Figure 8 is a similar view of the stop or locking 45 block equipped with a guide arm whereby the same is removably supported on the guide when detached from the holder. Figure 9 is a perspective view showing a form of stop guide made separate from the 50 holder.

Similar characters of reference refer to like parts throughout the several views.

Although my improved sash lock or fastener may be applied to windows of various constructions, the window, for example, 55 which is shown in the drawings comprises

a frame having an upright side piece 10, which is provided with inner and outer upright runways 11 and 12, a lower inner sash having an upright bar 13 guided in the inner runway 11, an upper bar 13, and an upper sash having an upright side bar 15 guided in the runway 12 and a lower horizontal bar 16, which is arranged horizontally in line with the upper bar of the inner sash when both sashes are in their closed position, as shown in Fig. 1.

My improved sash lock is preferably mounted on the lower end of the upright side bar 15 of the outer sash and adapted 70 to co-operate with the adjacent part of the inner sash for preventing relative vertical movement of these sashes with reference to each other, so that unauthorized entrance into the building will be prevented. 75

In the preferred form of this sash lock, as shown in Figs. 1—8, the same comprises a holder which is mounted on the outer sash and a stop block movably mounted on this holder and adapted to be engaged by the 80 inner sash. This holder preferably comprises a metal plate 17 secured in an upright position to the inner side of the outer sash bar 15 by means of screws 18 or otherwise and upper and lower hooks 19, 20 arranged 85 at the upper and lower ends of the face plate 17 and having their grooves facing each other, while the stop block 21, has generally the form of a downwardly tapering wedge which is provided at its upper and lower 90 ends with lugs 22, 22 adapted to engage with the hooks or seats 19, 20 and provided on its inner side with an inclined face 23 which inwardly overhangs the upper edge of 95 the inner sash.

The relative arrangement of these parts is such that when the stop block 21 is in its operative position on the holder the inclined face 23 on the stop block and the upper outer edge of the inner sash will engage with each 100 other if an attempt is made to lower the outer sash or raise the inner sash, thereby preventing either of these sashes from being opened at this time.

When this stop block is moved out of engagement with the holder and clear of the path of the inner sash, no obstruction is offered to the free downward movement of the outer sash or the upward movement of the inner sash, so that these sashes may then 110 be opened.

Means are provided for conveniently stor-

ing the stop block when the same is not in use, which means are so constructed that they serve to support the stop block at this time, but still maintain a mechanical connection between the same and the holder, so as to prevent the stop block from becoming displaced and instead retain the same always in a position where the same is available, ready for shifting into its operative position 10 for locking the sashes against vertical movement relatively to each other and preventing unlawful entrance into the building.

In the preferred construction for accomplishing this purpose a horizontal bracket 24 is provided which is connected at its inner end with one side of the base 17 of the holder and formed integrally therewith, this bracket being provided with a horizontal guide way 25 which is T-shaped in cross section and leads to an outwardly opening notch or recess 26 arranged at the outer end of the bracket 24. The stop block 21 is provided on its underside with an outwardly projecting T-shaped guide arm, the enlargement 27 of which is adapted to travel in the guideway 25 when the stop block is moved horizontally toward and from the holder while the reduced neck 28 of this arm is adapted to engage with the notch or recess 26 at the outer extremity of the bracket 24 and permit the stop block 21 to be swung outwardly from a position in which it is arranged in the path of the inner sash to a position in which it is out of the path of the sash, as shown by dotted lines in Fig. 1 and by full lines in Fig. 3.

As shown by full lines in Figs. 1 and 2, a stop block is engaged with the hooks of the holder and its inclined face 23 is arranged 40 in the path of the upper edge of the inner sash, in which position this block overhangs the inner sash and thereby prevents either of the sashes from being moved vertically relatively to each other. The movement of 45 this block toward the side piece of the window frame is limited by engagement of the enlargement or head 27 of the guide arm with a shoulder 29 formed between the inner end of the guideway 25 and the base plate 17, as shown in Figs. 2 and 3. The movement of the stop block away from the side piece of the frame and out of engagement from the holder may be prevented by a stop device which in its preferred form 50 consists of a locking pin 30 passing through corresponding openings 31 formed in the upper and lower parts of the bracket 24 adjacent to the holder, as shown in Figs. 1, 2, 4 and 6. Upon withdrawing the pin 30 the 55 stop block 21 may be moved by means of its supporting arm outwardly along the bracket 24 and thence swung downward to the outer end of this bracket in which its neck 28 and the supporting arm engages with the notch 26 and the locking block arranged out of

the path of the inner sash, as shown by full lines in Fig. 3, thereby permitting either one of the sash to be moved vertically into a more or less open position.

In Figs. 1, 2, 3, 6 and 7, the bracket 24 is shown formed integrally with the holder base 17. When desired this bracket may be formed separate from the holder, for instance, as shown in Fig. 9, the bracket 32 is formed on a separate attaching plate 33 which latter may be secured in place between the outer sash independently of the stop block holder, by screws or otherwise.

In addition to locking the sashes against the opening movement relatively to each other, means may be associated therewith for preventing rattling of the sashes under wind pressure when the same are closed. The preferred means for accomplishing this consists of two hooks 34 pivotally mounted on the upper edge of the inner sash so as to be capable of swinging into and out of engagement with the coupling pins 35 at opposite ends and into and out of a position on opposite sides of the stop block. These two hooks are connected at their rear ends by means of a wrist 36 which is pivoted on a plate 37 secured to the upper edge of the inner sash. When both sashes are closed and the two hooks 34 are in engagement with the coupling pins 35 and stand on opposite sides of the locking block 21, as shown in Figs. 1 and 2, the two sashes have their opposing parts held together so that the same are prevented from rattling under wind pressure, and the locking block 21 is also prevented from being withdrawn from its holder independently of the locking pin 30. Upon, however, swinging the coupling hooks 34 upwardly and inwardly out of engagement from the coupling pins 35, as shown in Fig. 3, the two sashes are uncoupled from each other and in the absence of the retaining pin 30 the rocking block 21 may be shifted into its inoperative position, so as to permit the sashes to be opened.

In order to permit the stop member 21 to move lengthwise of the guideway this stop member is provided with a notch 38 on its rear side in line with the flanges forming the guideway 25 on the bracket 24 which notch is adapted to receive these flanges and permit the stop to move horizontally along the same.

As a whole this sash lock and anti-rattling device is inexpensive in construction, and can be readily applied to windows now of general construction and when in use this device operates effectively to prevent illicit opening of the window sashes from the outside of the building and also insures against rattling noise of the same when subjected to the effects of the wind.

I claim as my invention:

1. A locking device for relatively movable

members comprising a holder adapted to be mounted on one of said members, a stop removably mounted on said holder and having an inclined face adapted to be engaged by the other member for preventing relative movement of said members, and a guide which extends laterally from said holder and upon which said stop may be moved for carrying the same out of the path of said 10 opposing member, said guide having a horizontal guideway which is T-shaped in cross section and said stop having a T-shaped arm which runs in said guideway.

2. A locking device for relatively movable members comprising a holder adapted to be mounted on one of said members, a stop removably mounted on said holder and having an inclined face adapted to be engaged by the other member for preventing relative 15 movement of said members, and a guide which extends laterally from said holder and upon which said stop may be moved for carrying the same out of the path of said opposing member, said guide having a horizontal guideway which is T-shaped in cross section and said stop having a T-shaped arm which runs in said guideway, and a detent removably mounted on said guideway adjacent to said holder for confining the stop on said 20 holder.

20 movement of said members, and a guide which extends laterally from said holder and upon which said stop may be moved for carrying the same out of the path of said opposing member, said guide having a horizontal guideway which is T-shaped in cross section and has its inner end arranged adjacent to said holder and its outer end arranged at a distance from said holder and provided with a rearward notch in its back, 25 and a T-shaped arm arranged on said stop and adapted to run in said guideway and to enter said notch for permitting said stop to be moved out of the path of said opposing member and to stand in a position 30 reverse to its operative position.

3. A locking device for relatively movable members comprising a holder adapted to be mounted on one of said members, a stop removably mounted on said holder and having an inclined face adapted to be engaged by the other member for preventing relative movement of said members, and a guide which extends laterally from said holder and upon which said stop may be moved for carrying the same out of the path of said 35 opposing member, said guide having a horizontal guideway which is T-shaped in cross section and said stop having a T-shaped arm which runs in said guideway and said guideway being provided at its inner end with a shoulder which is adapted to be engaged by the T-shaped arm and prevent its with-

drawal from the inner end of said guideway.

4. A locking device for relatively movable 55 members comprising a holder adapted to be mounted on one of said members, a stop removably mounted on said holder and having an inclined face adapted to be engaged by the other member for preventing relative 60 movement of said members and a guide which extends laterally from said holder and upon which said stop may be moved for carrying the same out of the path of said opposing member, said guide having a horizontal 65 guideway which is T-shaped in cross section and said stop having a T-shaped arm which runs in said guideway, and a detent removably mounted on said guideway adjacent to said holder for confining the stop on said 70 holder.

5. A locking device for relatively movable 75 members comprising a holder adapted to be mounted on one of said members, a stop removably mounted on said holder and having an inclined face adapted to be engaged by the other member for preventing relative movement of said members, and a guide which extends laterally from said holder and upon which said stop may be moved for 80 carrying the same out of the path of said opposing member, said guide having a horizontal guideway which is T-shaped in cross section and said stop having a T-shaped arm which runs in said guideway, and a detent 85 removably mounted on said guideway adjacent to said holder for confining the stop on said holder and consisting of an upright pin engaging with openings in the upper and lower parts of said guideway and extending across the path of said 90 T-shaped arm.

6. A locking device for relatively movable 95 members comprising a holder adapted to be mounted on one of said members, a stop removably mounted on the holder and adapted to be engaged by the other member, and means for coupling said holder and said last-mentioned member for preventing rattling comprising lugs arranged on the holder 100 on opposite sides of said stop, and hooks pivoted on said last-mentioned member and engaging said lugs.

HERMAN HOPF.
